UNITED STATES PATENT OFFICE.

AUGUST W. DONOP, OF CHICAGO, ILLINOIS, ASSIGNOR TO U. S. LIGHT & HEAT CORPORATION, OF NIAGARA FALLS, NEW YORK, A CORPORATION OF NEW YORK.

ELECTRIC REGULATOR.

1,319,855.

Specification of Letters Patent. Patented Oct. 28, 1919.

Application filed July 11, 1917. Serial No. 179,798.

To all whom it may concern:

Be it known that I, AUGUST W. DONOP, a citizen of the United States, residing at Chicago, in the county of Cook and State of Illinois, have invented new and useful Improvements in Electric Regulators, of which the following is a specification.

The present invention relates to electric regulators.

10 More particularly the invention relates to that class of electric regulators using a compressible pile as the variable resistance element. One difficulty with this type of regulator, as they have hitherto been constructed, 15 is that it is difficult to reduce the resistance of the compressible pile to a minimum and still maintain a wide range of regulation.

An object of the present invention is to provide a regulator of the compressible pile 20 type in which a maximum compression force will be exerted upon the pile when it is desired to reduce the resistance of said pile to a minimum and whereby smooth and accurate regulation of wide range may be secured.

A further object is to provide a regulator of simple and sturdy construction which will produce close regulation.

Further objects will be apparent as the 30 description proceeds.

The one figure of the drawing represents diagrammatically one embodiment of the present invention.

In the embodiment illustrated, a pair of 35 compressible piles 1, 2, are provided. These piles are arranged with their longitudinal axes parallel and are preferably of substantially the same dimensions. A yoke 3 is provided at each end of the piles 1, 2, each 40 of which yokes is adapted to be operated by a lever 4. Each of the levers 4, 4, is pivoted at the point 5 and has pivotal connection with its corresponding yoke 3, preferably by means of a socket joint 6. The levers 4, 4, 45 are normally urged toward one another by means of the spring 7, whereby the resistance of the piles 1, 2, is reduced to a minimum. The tension of the spring 7 may be adjusted by means of the nuts 8, 8.

50 The levers 4, 4, are adapted to be operated by means of a solenoid 9. This solenoid 9 is provided with pole pieces 10, 10, having arcuate pole faces. Coöoperating with each of the pole pieces 10, 10, is an armature 11, 55 also having an arcuate face conforming to

the face of its corresponding pole piece 10. The armatures 11, 11, are pivoted at the points 12, 12, and have pivotal connection with the levers 4, 4, at the points 13, 13. A tie-rod 14 is provided which is connected to 60 each of the armatures 11 whereby said armatures 11 will move in unison. To provide this result, the tie-rod 14 is connected to each of the armatures 11, 11, at a point lying in a straight line connecting the pivotal points 65 12 and 13. The point of pivotal connection of the tie-rod 14 with each of the armatures 11 should be equi-distant from the centers 12. In the arrangement illustrated, the pivotal point 13 is utilized for connecting one 70 end of said tie-rod. The opposite end of the tie-rod is connected to its corresponding armature 11 at the point 15.

It need not be explained that when the solenoid 9 is not energized, the spring 7 will 75 strongly urge the levers 4, 4, toward one another, whereby the resistance of the piles 1 and 2 will be a minimum. As the solenoid 9 becomes energized, the armatures 11 will be attracted against the tension of the spring 80 7 and will move the levers 4, 4, away from one another. Due to the arcuate form of the pole pieces 10, 10, and the armatures 11, 11, the pull of the solenoid 9 will be uniform. The tie rod 14 will constrain the armatures 85 11 to have equal increments of movement as the pull of the solenoid increases. Due to the pivoted connections of the yokes 3, 3, with the levers 4, 4, any tendency of the piles 1, 2, to operate unequally will be compensated for. If at any step of the action of 90 the regulator one of said piles should tend to take more than its share of the load, it will become heated more than the other pile and will expand, operating the yokes 3, 3, as levers about the socket joints 6 to increase the pressure on the pile which is tending to take less than its share. The increase of pressure on the lagging pile will so decrease its resistance that it will at once take its quota. 95

One embodiment of the present invention has been described in detail. Various modifications will occur to those skilled in the art. It is intended to cover in this patent all such modifications that come within the 100 scope of the invention as defined by the appended claims.

What I claim as new and desire to secure by Letters Patent of the United States, is—
1. In an electric regulator, in combina- 110

- tion, a compressible pile, operating levers at opposite ends of said pile, spring means for urging said levers to compress said pile, an electro-magnet having pole pieces with arcuate pole faces, armatures with arcuate faces coöperating with said pole pieces, each of said armatures being connected to one of said levers for operating same.
2. In an electric regulator, in combination, a plurality of compressible piles arranged with their longitudinal axes substantially parallel, operating means at opposite ends of said piles, spring means for urging said operating means to compress said piles, an electro-magnet having pole pieces with arcuate pole faces, armatures with arcuate faces coöperating with said pole pieces, each of said armatures being connected to one of said levers for operating same.
3. In an electric regulator, in combination, a compressible pile, operating levers at opposite ends of said pile, spring means for urging said levers to compress said pile, an electro-magnet having pole pieces with arcuate pole faces, armatures with arcuate faces coöperating with said pole pieces, each of said armatures being connected to one of said levers for operating same, and means for causing said armatures to move in unison.
4. In an electric regulator, in combination, a plurality of compressible piles arranged with their longitudinal axes substantially parallel, yokes capable of a levering action engaging adjacent ends of said piles, pressure means coöperating with said yokes, and an electro-magnet with its longitudinal axis parallel to the axes of said piles for operating said pressure means.
5. In an electric regulator, in combination, a plurality of compressible piles arranged with their longitudinal axes substantially parallel, pressure means for operating on both ends of said piles simultaneously, and an electro-magnet having its longitudinal axis parallel with the axes of said piles for moving said pressure means.
6. In an electric regulator, in combination, a plurality of compressible piles arranged with their longitudinal axes substantially parallel, pressure means for operating on both ends of said piles simultaneously, and an electro-magnet having its longitudinal axis parallel with the axes of said piles for moving said pressure means.
7. In an electric regulator, in combination, a compressible pile, operating levers at opposite ends of said pile, spring means for urging said levers to compress said pile, an electro-magnet having pole pieces with arcuate pole faces, armatures with arcuate faces coöperating with said pole pieces, each of said armatures being connected to one of said levers for operating same, said armatures being connected to move in unison.
8. In an electric regulator, in combination, a plurality of compressible piles arranged with their longitudinal axes substantially parallel, operating means at opposite ends of said piles, spring means for urging said operating means to compress said piles, an electro-magnet having pole pieces with arcuate pole faces, armatures with arcuate faces coöperating with said pole pieces, each of said armatures being connected to one of said levers for operating same, said armatures being connected to move in unison.
9. In an electric regulator, in combination, a plurality of compressible piles arranged with their longitudinal axes substantially parallel, pressure means for operating on both ends of said piles simultaneously, and an electro-magnet having its longitudinal axis parallel with the axes of said piles for moving said pressure means, said electromagnet having pole pieces with arcuate pole faces and armatures with arcuate faces, said armatures being connected to said pressure means, said armatures being connected together whereby they are constrained to move in unison.

In witness whereof, I have hereunto subscribed my name:

AUGUST W. DONOP.
